ELECTRIC PAINT REMOVER

Louis M. Carpenter, Syracuse, N. Y.

Application July 24, 1948, Serial No. 40,601

4 Claims. (Cl. 219—29)

1

The invention relates to electric paint removers for use in burning off paint from a painted surface.

In the past it was considered that the best method of removing old paint from a painted surface was to burn the paint from the surface by employing a gasoline blow torch. Although such a blow torch was effective for this purpose there were several serious objections to its use. It was heavy and awkward to use and it required a considerable degree of skill on the part of the operator thereof to properly project the flame of the torch along the painted surface at the right speed so as to effect an efficient melting of the paint and at the same time to follow the torch with a scraper blade at a correct distance therefrom to strip the melted paint from said surface. Also, with a blow torch, even in the hands of an experienced operator, there was always a constant danger that the flame of the torch would enter into cracks in the woodwork or other surfaces being operated upon and thus a fire would be started within the walls of the painted structure, which would possibly not be detected until sometime after the torch had been used.

To overcome the deficiencies and hazards present when a blow torch is used for removing paint from coated surfaces, there have been developed in recent years different types of electric paint burner devices which have been designed and intended to provide a burning heat to dissolve or disintegrate the paint film from a painted surface. Although some of these electric paint removers have been capable of generating a sufficient amount of heat to effectively remove the paint film, they have been found to be impractical in use for several reasons. In many of these paint removers, the heating elements used therein do not correctly concentrate or distribute the heat over the painted surface being treated so that a stripping of the paint can be accomplished efficiently or at a rapid rate. In others, because of their construction, the heating elements used do not stand up and have a short life, thus making frequent replacement of the heating elements necessary. In addition to these defects, in other of these electric burner devices, the construction thereof has been such that the heat generated by the heating elements tends to heat up the entire device to such an extent that the operating handle thereof becomes so hot that it is necessary for the user to wear heavy gloves to protect the hands. Furthermore, in some of these prior electric paint remover constructions, which may be termed "open element burners" (because the heating ele-

2

ments thereof are mounted in an exposed condition) the heating elements are positioned so far away from the painted surface that the heat transfer therefrom is not sufficient to properly effect a disintegration of the paint regardless of the amount of heat generated by the said heating elements. In other devices of the open element type, where the heating elements are positioned close enough to the painted surface, the burner has proven to be impractical in use because the paint melted by the heat from the heating elements tends to get into the heater coils and thus cause said coils to be short circuited and the burner rendered unusable. Finally, the use of these open element types of electric paint removers presents a personal hazard because of the possible chance that the user's hands, or his clothes, may accidentally come into contact with the exposed heating elements.

20 In other types of electric paint removers heretofore used the heating elements thereof have been imbedded in a block of refractory material in order to protect the same from injury. In these constructions the conduction of the heat supplied

25 by the heating elements to the surrounding mass of refractory material, greatly decreased the efficiency of the heat radiation of the paint remover. In other words, the heat that is supplied by the heating elements is conducted away therefrom into the surrounding mass of refractory material rather than converting itself into radiant energy which can be directed towards the painted surface to be operated upon.

It has also been found that one important feature with respect to the efficiency in use of an electric paint remover, is that the heating elements thereof should produce a high concentration of heat along the outside edges of the device. If such concentration of the heat is not produced at such points the paint will only become properly melted in the central area of heating and will become cooled off so rapidly along the edges of the device that the paint cannot be properly stripped off, and it will gum up on the edges of 40 the scraper blade which is customarily used in conjunction with the paint remover. To overcome this difficulty of not having a proper concentration of the heat along the outside edges of the paint remover, devices have been developed 45 which have been provided with a housing over the heating elements which is made of aluminum, and which aluminum housing is possessed with a shiny heat reflecting surface on the interior thereof of which functions to reflect the heat rays, radiating from the heating element, downwardly and 50 55

toward the outside edges of the device. In these constructions, however, the shiny surface of the aluminum metal of the housing does not stand up under the intense heat conditions produced by the heating elements and the said surface becomes smoked up and dulled, and then the paint being removed from the painted surface gets into the reflecting housing. This smoking and dulling of the shiny surfaces of the housing is also undesirable because then the effect of the focus of the indirect radiant rays of heat is lost, thus upsetting the proper distribution thereof along the outer edges of the device. Furthermore, as soon as the shiny surfaces of the aluminum housing disappear the radiant heat will no longer be reflected, but rather will be absorbed by the darkened surfaces of the housing and the constant absorption of the heat will build up the temperature of the aluminum metal to a point whereby it will be radiated upwardly and be conducted to the operating handle of the device, and thus make said handle so hot that it will be uncomfortable to grasp.

A further deficiency in the construction of some of the prior electric paint burners has been that the heating elements used therein have been comprised of a grid formed of short lengths of resistance wire which have been fastened together in series, and high heat intensity has been provided by using different sized resistance wire on the outside edges of the grid. While this arrangement of the resistance wires serves to produce a proper distribution of the heat, it necessitates the use of a multiplicity of short coils of resistance wire which are fastened together with each fastening point contributing a potential weak point in the construction under severe heat conditions.

It is the main object of the present invention to provide an electric paint remover device which is designed and constructed in such a manner that the many deficiencies of construction and operation which exist in prior devices of this type, some of which have above been referred to, are overcome, and which is also constructed so that the heating element thereof will generate sufficient intense heat to efficiently disintegrate the paint film on a painted surface so that said paint film may be rapidly stripped or scraped off such surface.

A further object is to provide an electric paint remover in which the heating means thereof is so arranged and constructed that it will be adequately protected and shielded against oxidation or deterioration and against mechanical injury.

A further object is to provide an electric paint remover construction provided with a heating means which may be brought into close relation to a painted surface without danger of fire or electrical hazard and without injury to the heating means and also without said means becoming gummed up or mechanically or electrically damaged by the heated plastic paint.

A further object is to provide an electric paint remover construction which has an aluminum reflecting shield so arranged and positioned with respect to the heating means, and protected, that it will not lose its reflectivity or be affected by the heat generated by the heating means.

A further object is to provide in an electric paint remover, an aluminum reflector for the heat rays produced by the heating means thereof, which reflector is provided with both an upper and lower shiny surface, the lower shiny surface being adapted to turn back reflectively most of

the heat rays from the heating means reaching it and to direct said rays downwardly toward the heating means, and the upper shiny surface functioning to block off the small portion of said heat rays which will not be reflected by the lower shiny surface and which ordinarily will be conducted upwardly through the metal of said shield and cause the operating handle of the paint remover to heat up.

A further object is to provide a heating means for an electric paint remover which will provide a higher heating temperature than has been produced by heating elements heretofore used in electric paint removers, and which will also have a longer life of use at high temperatures than has been possible with heating elements previously used.

A further object is to provide an improved construction of insulating block for supporting the resistance wires of the heating element.

A further object is to provide a novel assembly of an insulating block in which the heating means is embedded and a metal sub-shield, so that said insulating block and said sub-shield comprise an efficient heat radiating unit with low conduction losses.

A further object is to provide an assembly of an insulating block having the resistance wire of the heating means embedded therein, with a metallic sub-shield, and so that the insulating block will be held by said sub-shield at an effective predetermined distance above a painted surface to be heated by the paint remover device.

A further object is to provide an electric paint remover construction having a stainless steel sub-shield support for an insulating block in which the wire coils of a heating means are embedded, and which shield is so mounted with respect to said block that any tendency of the block to warp at its ends due to the heat conditions to which it is subjected will be eliminated.

A further object is to provide an electric paint remover device having a stainless steel shield for the insulating block in which the heating coils are imbedded, and which shield is so formed that it will provide a barrier along the edges of the block which will prevent outward chilling of the paint film being removed, and also will function to retain within its walls the heat produced by said heating coils.

A further object is to provide in an electric paint remover device a stainless steel shield support for the insulating block in which the heating coils of the device are embedded, and which shield together with said block forms as a whole a practical composite unit which may be readily and quickly replaced as a unit in the burner construction.

A further object is to provide in an electric paint remover, a sub-shield construction for supporting an insulating block in which the heating coils of the paint remover are positioned, and which shield is secured to said block in such manner that the conducted heat to the shield from the block is reduced to a minimum.

A further object is to provide an electric paint remover construction which is adapted to be positioned in an upside down position on any surface, during warmup periods, and so that it will be supported on one corner of the reflecting shield and the handle thereof, and without danger of the burner damaging the surface upon which it is so positioned.

With the above and other objects in view, the

invention consists in the construction, arrangement and combination of the various parts of the paint remover device, where the objects contemplated are attained, as hereinafter more fully set forth, pointed out in the claims and illustrated in the accompanying drawings, in which

Figure 1 is a side elevational view of the electrical paint remover embodying the features of my invention;

Figure 2 is an end elevational view of the paint remover and wherein parts of the interior construction thereof are indicated by spaced lines;

Figure 3 is a top plan view with parts thereof shown broken away to more clearly indicate the construction;

Figure 4 is a bottom plan view showing the insulating block in which the heating elements of the burner are embedded;

Figure 5 is an elevational side sectional view of the burner construction.

Referring particularly to the drawings, the electric paint remover of my invention includes in its construction a rectangular shaped insulating block member A; the heating wire coils indicated generally at B; a sub-shield C; a reflector shield D; a terminal cover E; the handle member F; handle brackets G; and electrical conductor cord H extending through said handle; the terminal bushings I; and the terminal tube covers J which are adapted to enclose the ends of the wires of the heating coils.

The rectangular shaped insulating block may be made of porcelain or any other suitable non-conducting heat resisting material and is provided with a plurality of shallow grooves or channels 1 in the lower face thereof which extend lengthwise of said block (see Fig. 4). Mounted in said grooves or channels is the coiled current conducting resistance wire B which forms the heating means of the paint remover. The resistance wire used for the heating means is of the type known as "Kanthal wire." This particular type of wire has been found to possess characteristics which are not found in other types of electrical resistance wire which have heretofore been used in electric paint remover constructions and is adapted to operate at a higher temperature than other types of wire used for electrical heating means. Also, a heating means employing "Kanthal" wire requires less wire per unit of heat than most other resistance wires and, therefore, provides more heat in a given area than is possible when other types of wire, such for instance as "Nichrome" wire are used. This type of resistance wire also has a longer life in use at high temperatures than is possessed by other wires. The resistance wire coils B of the heating means are positioned in the grooves or channels 1, of the insulating block A and are retained therein and insulated so as to prevent accidental contact therewith by the operator of the paint remover device, by means of a cement indicated at 3 (see Fig. 5). I have found that "Sauereisen Cement No. 78" is preferable for use in securing the resistance wire coils in the grooves of the porcelain block as other types of cement have proven to be unsatisfactory because they either break down to a powder under the severe heat conditions produced by the heating coils, or they are not sufficiently adhesive in the presence of the heat produced to properly retain the wire coils in place in said grooves, or they are possessed of such a complete insulating characteristic that they will obstruct a proper transfer of heat from the heating coils. "Sauereisen Cement" has the

advantage over other types of cement in the fact that it is not only high in heat conductivity but it is also low in electrical conductivity, and even though the heating coils are embedded and covered with the same, radiation of heat from the block will not be greatly impaired. This type of cement, when it has set, also provides a porcelain-like surface over the face of the grooves and forms a protection against the coils coming in contact with the user of the device.

Secured to the porcelain block A, and positioned in spaced relation thereto, by means of the screw bolts 4 and the nuts 5, is the sub-shield C. The sub-shield is preferably made of stainless steel and is formed so that it is provided with a top portion which completely covers the top surface of the block A, and with the side walls 6 and 7 which extend downwardly and enclose the side walls 8 and 9 of said block. The screw bolts 4 and the nuts 5 secure the sub-shield to the block at four separated points along the center line of the channel formed by the shape of the sub-shield as clearly indicated in Figures 2 and 4. These four small area points of contact are the only points of contact between the block and the sub-shield, and thus the paths for conducting heat from the block to the sub-shield are reduced to a minimum.

The sub-shield C, together with the porcelain block A, with the resistance wire B embedded therein, comprise the heating unit of the paint remover construction, which heating unit is of light weight and can be readily and easily removed from the paint remover construction and replaced by another similar heating unit if desired.

The sub-shield C performs several important functions in the paint remover device of the invention. It provides a rigid longitudinal support for the porcelain insulating block A, and prevents said block from warping at its ends from the heat transmitted to it by the heating coils. The sides 6 and 7 of the sub-shield hold the insulating block at a required distance above the painted surface to be heated by the heating coils, and the side member 6 provides a cleaning edge for cleaning paint from the scraper blade which is used in conjunction with the paint remover device. The sub-shield also forms a partial block to upward flowing radiant heat coming from the heating coils and a complete barrier to convected heat. It also provides a barrier along the edges of the porcelain block to outward chilling of the paint surface being treated by the paint remover device and also functions to retain the heat produced by the heating coils within its walls. The method of mounting the porcelain insulating block along the center line of the channel formed by the shape of the sub-shield also gives to the block a certain amount of resiliency so that it is capable of absorbing shocks which ordinarily would cause a more rigidly mounted block to break or crack. Lastly, the sub-shield serves as a smoke shield and protects the reflective surface of the aluminum shield D, which is to be further described, from smoke and paint debris which would ordinarily tend to destroy the reflectivity of said aluminum shield if the sub-shield was not used.

Positioned above the sub-shield C is the reflector shield D, which is preferably made of aluminum. The reflector shield is adapted to stop the upward flowing radiant rays of heat coming from the heating coils B, and to reflect the same downwardly towards the heating means. The reflector

shield is made so that it is provided with a shiny upper surface 32 and a lower shiny surface 33. The lower shiny surface 33 functions to reflect back most of the heat rays from the heating coils which reach it, and the small portion of said heat rays which are not reflected back but which are conducted upwardly through the metal of the shield are stopped at the upper shiny surface 32, said surface having a low emissivity factor and thus will not re-radiate the heat rays that may reach it.

The aluminum reflector shield D is mounted above and in spaced relation to the sub-shield C, by means of three screw bolts 10, 11 and 12, and the spacing bushings 10', 11' and 12', and is formed with the curved downwardly extending sides 13 and 14, which overlap the sides 6 and 7 of the sub-shield C. It will be noted that the curved side 13 of the reflector shield does not completely overhang the sub-shield along one side of the paint remover. The curved side 13 is purposely formed in this manner and so that it is in line with the side 6 of the sub-shield and does not overhang the same, and so that the paint remover device may be moved directly into corners when it is being used. As is well known, there are times during the removing of paint from a painted surface that it is necessary to get into corners or up to an upright, such as underneath a cornice, or on a floor close to the mop board, and the arrangement of the curved side 13 of the reflector shield with respect to the side 6 of the sub-shield, permits the burner device to be operated so that it can be readily moved into such places.

Extending through the aluminum shield D, and also through the sub-shield C are the openings 15 and 16 through which the free ends 17 and 18 of the "Kanthal" wire of the resistance coils of the heating means extend. Positioned in said openings 15 and 16 are the porcelain insulating tubes J which surround the ends 17 and 18 of the resistance wire and extend upwardly within the terminal cover E. The ends 17 and 18 of the resistance wire are adapted to be secured to the wire ends 19 and 20 of the electrical conductor cord H which extends through the wooden handle F of the paint remover device. It will be noted that it is intended that the ends 19 and 20 of the wire of the electrical conductor cord H be connected directly to the ends 17 and 18 of the resistance coil wires by wrapping the ends of the electrical conductor wires around the doubled back ends of the resistance wires and then binding the connection by means of the solderless conically threaded thimble-shaped insulating bushings I, which function not only as binders for the connection but also as electrical insulators to enclose said connection.

The terminal connection which is provided between the ends 17 and 18 of the heating element wires and the wire ends 19 and 20 of the electrical conducting coil H, is one of the novel features of the construction of the paint remover device of the present invention. In the usual electric paint remover constructions the ends of the resistance wires of the heating means are brought to terminal screws on a plate mounted in the handle attachment of the device. This is common practice in connection with the construction of medium temperature electrical burner devices, but such an arrangement would cause constant trouble in a burner device using high temperatures in trying to maintain good contact, unless the contacts were actually welded

to the plate. In the present construction the ends of the resistance wires are brought out to a relatively cool area and then are bent back on themselves to reduce the resistance of the wire at this point below the self heating point and so that they are cool except for the heat conducted through the metal of the wire, and at this point they are connected directly with the ends of the wires of the electrical conductor cord H.

Secured to the base portion 21 of the wooden handle F by means of the screw bolts 22 and 23 and nuts 24 and 25, are the vertically extending legs 26 and 27 of the handle brackets G. The horizontally extending legs 26' and 27' of said brackets extend lengthwise over the top of the aluminum shield D, and are secured at their ends 28 and 29 to the shield by means of the screw bolts 10 and 11. The handle brackets are made so that the legs thereof are held to a minimum in cross-section and so that they will not provide too large a path for the passage of conducted heat from the heating coils. It will also be observed that the handle F of the paint remover construction is not connected directly to the aluminum shield D, but is only connected thereto through said brackets G. This arrangement also provides for a cool operating handle for the paint remover construction.

Secured to the base portion 21 of the handle member F, by means of the screw bolts 22 and 23, and the nuts 24 and 25, is the rectangular shaped, three-sided terminal cover E which is adapted to enclose the terminal connection of the ends of the wires from the heater coils and the ends of the wires of the electrical conductor cord H. The terminal cover E is provided with the slotted openings 34' and 35' in the side walls 34 and 35 thereof, which slotted openings are adapted to receive the screw bolts 22 and 23. By reason of said slotted openings 34' and 35' said terminal cover may be removably secured to the base portion 21 of the handle F, and thus may be readily taken off of the paint remover device so that the terminal connection of the wires 17, 18, 19 and 20 may be inspected or repaired when necessary by merely loosening up on the nuts 24 and 25.

Mounted within the terminal cover E and positioned over the terminal connection made between the heating element wires 17 and 18 and the wire ends 19 and 20 of the conductor cord H, are the ceramic solderless thimble-shaped bushings I. These terminal bushings provide an effective means for joining dissimilar metals such as "Kanthal wire" used for the heating coils and the copper wires used in the electrical conductor cord, operating under severe heat conditions, and there will thus occur no breakdown of the connection of the wires due to oxidation of the copper wire and also good contact between the two types of wire will be definitely maintained.

It will be seen from the above description of my improved electric paint remover that it incorporates therein many novel features of construction which are not found in prior paint removers of this type or which overcome the defects in construction and operation which have existed in such paint removers. It will also be obvious that my invention is susceptible to some change and modification without departing from the principles and spirit thereof, and for this reason I do not want to be understood as limiting myself to the precise arrangement and formation of the several parts herein shown in carrying out my invention, except as hereinafter claimed.

75 I claim:

1. An electric paint remover comprising an electric heat radiating means imbedded in an insulating support, a metallic shield secured to and in spaced relation to said heat radiating means and forming a heat confining housing enclosing said heat radiating means, a metallic shield of high heat reflectivity secured to said first mentioned shield and mounted above and in spaced relation thereto forming an air space therebetween, an operating handle mounted on said heat reflecting shield through connectors of reduced cross section, and electrical conductor means extending through said handle and connected to said heating means for supplying electric current thereto.

2. An electric paint remover comprising an electric heat radiating means imbedded in an insulating body, a metallic shield secured to and in spaced relation to said heat radiating means through connectors of substantially reduced cross section and forming a heat confining housing enclosing said heat radiating means, a metallic heat reflecting shield secured to said first mentioned shield through connectors of reduced cross section and mounted above and in spaced relation thereto, and having reflecting surfaces on the under and upper faces thereof, said under reflecting surface being adapted to reflect downwardly heat rays radiating upwardly from said heating means and from said first mentioned shield and said upper reflecting surface being adapted to block the upward flow of heat rays conducted through the metal of said shield, an operating handle mounted on said heat reflecting shield, and electrical conductor means extending through said handle and connected to said heating means for supplying electrical current thereto.

3. An electric paint remover comprising an electric heating means positioned in the lower face of a rectangular shaped block of non-conducting and heat resisting material, a metallic heat blocking shield positioned over said block and secured in spaced relation to the same through connectors of reduced cross section and so as to provide an air space between said block and shield, said shield being formed with downwardly extending side portions which enclose the sides of said block and which support said block a

predetermined distance above the painted surface to be treated by said paint remover, a metallic heat reflecting shield having upper and lower surfaces of high reflectivity positioned over and secured in spaced relation to said first mentioned shield, a hollow operating handle for the paint remover secured to the top of said heat reflecting shield, and an electrical conductor means extending through said handle and connected to said heating element for supplying electrical current thereto.

4. An electric paint remover comprising an electric heating means positioned in a rectangular shaped block member made of a non-conducting and heat resisting material, a metallic shield mounted over and secured to said block member and in spaced relation thereto and having downwardly extending side walls and open ends, said side walls enclosing the sides of said block member and also being adapted to support said block member a predetermined distance above the painted surface to be heated by the heating means of the paint remover, said shield and block member forming a complete assembly adapted to be removably positioned as a unit in the paint remover, an aluminum shield having heat reflecting surfaces secured to and over said first mentioned metallic shield and in spaced relation thereto, an operating handle secured to said aluminum shield for manipulating the paint remover, and an electrical conductor means extending through said handle and connected to said heating means for supplying electrical current thereto.
